ABSTRACT OF THE DISCLOSURE

The present disclosure is directed to a closet-forming structure which may be flat-folded for storage, shipping, and easy handling, and which may be simply erected in minimized time by an unskilled layman without any tools whatever, and placed flush against a floor, wall, and a ceiling to form a finished, six-sided closet of floor-to-ceiling height. The new structure is essentially three-layered, when collapsed, and includes a front wall panel and side wall panels permanently articulated thereto. A self-contained door is included in the front wall panel, while shelf and/or drawer supports are included in the side walls. Slidable, auxiliary wall members are included at the upper portions of all three walls and may be manually adjusted to effectively project the closet walls up to and against a ceiling to provide the finished closet with a full, floor-to-ceiling configuration.

Summary of the invention

With rising labor costs and the scarcity of trained, skilled carpenters, the costs of building any institutional building, home dormitory or the like has become prohibitive. For example, among the items usually consuming substantial labor and adding significantly to the cost of the completed building is the cost of an ordinary closet. That is to say, a most significant portion of the actual cost of a closet is often the many hours of skilled labor involved in building and installing the closet, *in situ*. Accordingly, it is a primary object of the present invention to provide a collapsible closet-forming construction which may be installed by unskilled labor in little time, with little effort, and no tools.

The new closet-forming structure includes three consecutively articulated wall panels, within the central one of which a bifold door is hung. The two outermost wall panels include shelf clips or similar mechanical fasteners to which a main bracing shelf spanning the gap therebetween may be joined simply and without tools. Installation of the main shelf automatically squares the unit (i.e., provides it with a rectangular cross section) and establishes a stable and rigidified structure having completely open top, bottom, and rear sides. The new structure is adapted to be erected on a building floor at a desired closet site and slid against a building wall to close off the open top and rear sides to provide a rear wall and bottom wall for the finished closet.

As mentioned hereinabove, the wall panels each include adjustable, auxiliary members at the upper edges, which members may be extended flush with the ceiling to close the remaining sides of the closet and to provide the closet with a top wall. Thus, when the closet-forming structure is placed in position against the wall, floor, and ceiling surfaces at the closet site, a complete, floor-to-ceiling closet will be formed. The new closet may be further rigidified by inserting a coat rod between the two side walls. The rod may also be installed without tools

2

merely by placing it in semi-circular socket elements installed on each of the side walls.

For a better understanding of the present invention, reference should be made to the following detailed description taken in conjunction with the accompanying drawings, in which:

- FIG. 1 is a perspective view of a completely erected and installed closet embodying the principles of the invention;
- FIG. 2 is a cross-sectional view of a squared closet-forming structure;
- FIG. 3 is an end view of the closet-forming structure in its flat-folded condition;
- FIG. 4 is a fragmentary, cross-sectional view of an installed closet taken along lines 4—4 of FIG. 1 and showing details of construction; and
- FIG. 5 is an enlarged, cross-sectional view taken along lines 5—5 of FIG. 4 showing a detail of the mounting of an auxiliary wall member to a wall panel.
- Referring now to FIG. 1, the completed closet includes a front wall 10, side walls 11 and 12 articulated to the front wall, and rear wall formed by a permanent structure, i.e., building wall W, floor F, and ceiling C. As shown, the front wall includes a jamb 13 and saddle 14 which define an opening in which a door 15 is mounted. Advantageously, the door 15 is of bifold construction and is supported on appropriate tracks 16.

As an important aspect of the invention, auxiliary wall members 17, fabricated from molding, are slidably mounted for selective vertical movement to each of the wall members 11, 10 and 12, by suitable, concealed friction mounting means. For example, the auxiliary wall members 17 may be grouted in a dovetail fashion to form keyways 19 (FIG. 5) which are blind at one end. Screws 20 having tapered heads 21 similar in configuration and dimension to that of the cross section of the keyways may be driven into the upper portions of each of the front and side walls of the closet, as shown in FIG. 1, to support the members 17. In other words, the screw heads act as keys which hold the members 17 by friction fits to the upper portions of the wall panels. As will be understood, suitable adjustment of the members 17 may be had merely by forcing the moldings upwardly or downwardly over the screw heads 21. Thus, the height of the closet can be varied by an amount equal to the length of the keyways 19. For example, in a closet designed for installation in a room having nominal eight foot ceilings, the height of the closet may be varied from seven feet ten inches to eight feet two inches.

As an important aspect of the invention and as shown in FIGS. 2 and 3, the side wall panels 11, 12 are each articulated to the front wall panel 10 by internally disposed hinges 22, 23 which are concealed when the structure is erected. As will be appreciated, this enables the side walls 11, 12 to be folded inwardly upon the main wall into a three-layered structure, as shown in FIG. 3, for storage, shipping, and easy handling. For example, when the wall panels are fabricated from $\frac{3}{4}$ inch stock, acceptable by all building standards for durable closets, the flat-folded structure will be less than $3\frac{1}{2}$ inches in thickness.

As a further important aspect of the invention, in order to accommodate the complete flat-folding of the side wall panels 11, 12, which are greater than half the width of the front wall, the side wall panel 12 is hinged in an offset manner from the plane of the front wall panel 10. As shown in FIG. 3, the hinges 23 are supported by an offset

post 24 which is approximately equal in width to the thickness of the wall panel 11. In this fashion it will be possible for the side wall panel 11 to be folded first and then the side wall panel 12 to be flat-folded thereover.

The side walls 11, 12 also include female shelf clips 25, coat rod sockets 26 formed by blind holes, and two vertical rows of $\frac{1}{4}$ inch hardware holes 27, in which standard $\frac{1}{4}$ inch shelf pins 28a or new drawer guides 28b may be selectively disposed, as shown in FIG. 4. For dust-free, flush mounting of the side wall panels 11, 12 against the baseboard of the wall W, the corners of the panels may be formed of compressible plastic foam pads 40, as shown in FIG. 1. As will be understood, the foam pads will conform themselves to the specific contour of the baseboard.

In accordance with the invention, the closet-forming structure of the invention is squared and rigidified by an upper main bracing shelf 30 which includes male shelf clips 31 at each end thereof. Advantageously, the main bracing shelf 30 includes edging strips 32 suitably attached thereto. When found desirable or necessary, a lower main bracing shelf 36, similar to the shelf 30, may be included in the closet-forming structure.

Further rigidification of the closet-forming structure is obtained by the installation of a coat rod 33 and additional shelves 34 or drawers 35 supported at selected levels of the closet by the shelf pins 28a and the new drawer guides 28b all of which may be installed without tools. The new drawer guides are formed from $\frac{1}{4}$ inch wire and, as shown in FIG. 2, are of a shallow U-shape having legs 42 spaced identically to the center to center spacing of the vertical rows of hardware holes 27. Thus, as an important aspect of the invention, the drawers 35 and the shelves 34 may be interchangeably arranged, as desired, using common hardware holes 27.

Specifically, the drawers 35 and shelves 34 are of full closet width but are of not substantially more than half the depth of the closet. As shown in FIG. 4, the outer sides of the drawers 35 include grooves 43 through which the drawers 35 will be slidably supported by the guides 28b for movement between the wall W and the front wall panel 10 and, thus, will be "openable" within the closet. Advantageously, when the new close-forming structure is installed in dormitories and the like, the utilization of the new closet-forming structure as a casing for a plurality of drawers 35, as shown in FIG. 1, will often eliminate the necessity of providing a separate case of drawers.

As will be appreciated, a floor-to-ceiling closet may be erected without tools, in accordance with the invention, in less than ten minutes by an unskilled workman or a layman. The flat-folded structure is merely opened and the coat rod 33 inserted in the sockets 26 formed on the opposite wall panels 11, 12. Parenthetically, it should be noted that, absent the hinging of the side wall panels 11, 12 to the front wall panel 10, it would not be possible to support a coat rod by opposed cylindrical wall sockets. Thereafter, through the open rear portion, the main bracing shelf 30 is locked in place by joining the shelf clips 31, 25, thereby squaring and rigidifying the structure. Additional shelves may be installed by setting them over the shelf pins 28a. In accordance with the invention, the drawers 35 may be simply installed through the rear opening in the closet by sliding the grooves 43 horizontally over the guides 28b. At this stage of the erection, the closet-forming structure is moved flush against the wall W, and the auxiliary members are pushed up flush against the ceiling C to form a complete closet. Advantageously, the dimensions of the structure are appropriately chosen in relation to the room in which the closet is to be formed, such that the squared structure cannot be tipped over. That is to say, the clearance between the ceiling and the rearmost edges of the members 17, in their minimally projected positions, is such that pivoting of the entire structure forwardly about an axis passing through the saddle 14 would cause the edges of members 17 to strike the ceiling.

The "tip-proof" nature of the closet-forming structure provides a desirable safety factor.

As should be understood, the completed closet may be permanently anchored to the wall W through holes 41 formed in the rearmost shelf edging 32 or through separate standard cleats, if desired. Moreover, it will be appreciated that the closet-forming structure of the invention may be fabricated in any size from wood, metal or any other commonly available structural material, prefinished or otherwise.

It should be understood that the specific structure herein illustrated and described is intended to be representative only, as certain changes may be made therein without departing from the clear teachings of the disclosure. Accordingly, reference should be made to the following appended claims in determining the full scope of the invention.

I claim:

1. A collapsible closet-forming structure including
  - (a) a front wall panel including members defining a door frame;
  - (b) a door supported by said front wall panel for opening and closing movement within said door frame;
  - (c) side wall panels articulated to said front wall panels;
  - (d) auxiliary wall members slidably mounted at upper portions of said wall panels for limited predetermined displacement relative thereto;
  - (e) a bracing shelf member of full closet width and having first locking means at its ends; and
  - (f) second shelf-locking means, adapted to cooperate with said first shelf-locking means, mounted on the inner surfaces of said side wall panels.

2. A closet-forming structure in accordance with claim 1 in which

- (a) said auxiliary wall members are supported in adjusted relation to said wall panels by frictionally held key means.

3. A closet-forming structure in accordance with claim 1, in which

- (a) one of said side wall panels is articulated to said front wall panel by a hinge having its pivot axis generally at the plane of said front wall panel; and
- (b) the other of said side wall panels is articulated to said front wall panel by a hinge having its pivot axis offset from the plane of said front wall panel by a distance substantially equal to the thickness of said one side wall panel.

4. A closet-forming structure in accordance with claim 1, in which

- (a) the lower rearmost corner portions of said side wall panels are formed by a compressible foam element.

5. A closet-forming structure in accordance with claim 1, which includes

- (a) rod supporting means disposed at the inner surfaces of said side wall panels; and
- (b) a coat rod adapted to be supported by said means.

6. A closet-forming structure in accordance with claim 1, which includes

- (a) a plurality of common hardware holes formed in spaced, vertical rows at the inner surfaces of said side wall panels; and
- (b) adjustable shelf and drawer supporting elements associated with selected ones of said holes.

7. A closet-forming structure in accordance with claim 6, in which

- (a) said drawer supporting elements are formed of a U-shaped wire the legs of which are spaced apart a distance equal to the spacing of said vertical rows;
- (b) said shelf supporting elements are shelf pin means having the same diameter as said wire.

8. A closet-forming structure in accordance with claim 1, in which

- (a) at least one drawer of full closet width adapted to be supported by said supporting elements;

- (b) said drawer being of substantially less than full closet depth.
9. A closet-forming structure in accordance with claim 1, in which
- (a) said auxiliary wall members are fabricated from 5 molding strip.
